CALCULATING MACHINE

Walter J. Pasinski, Howell, Mich., assignor to
Burroughs Adding Machine Company, Detroit,
Mich., a corporation of Michigan

Application July 29, 1936, Serial No. 93,129

11 Claims.

(Cl. 235—15)

This invention relates to cash registers, and more particularly to a key coupler and pre-set mechanism for a cash register of such construction as to provide a machine with a flexible keyboard.

The invention is an improvement applicable to the standard Burroughs cash register machine of the type illustrated by my copending applications, Serial Nos. 689,656 and 689,657, filed September 15, 1933, now Patents Nos. 2,070,059 and 2,070,060, respectively, issued February 9, 1937. To correct an error in one order of the amount indexed on the keyboard in a machine embodying the pre-set mechanism and key coupler therein disclosed, it is normally necessary to depress the pre-set key to release the depressed keys of all orders from pre-set position. Thus, if the No. 6 key of the cents order had been depressed by mistake so that the amount indexed on the keyboard was \$1.26 instead of the desired amount \$1.25, it was necessary to release the depressed keys of the hundreds and tens orders along with the cents order by rapidly depressing the pre-set key. This meant an additional operation of the pre-set key to release the keys and also re-indexing the amount in each order on the keyboard.

With a machine of the above type, if the error was noted when the machine was pre-set, a skillful operator could slowly manipulate the pre-set key in order to slowly raise the key coupler to release in the order named the cents key, then the tens key and finally the hundreds key. This, however, was a slow and difficult method of correcting errors made in indexing the keyboard and, obviously, was not adapted to general commercial use when rapid manipulation of the machine is necessary.

Therefore, it is an object of my invention to provide a cash register having a flexible keyboard.

It is another object of my invention to provide an improved cash register in which an error in the amount set up on the keyboard may be corrected with maximum speed and minimum operation.

It is a further object of my invention to provide a cash register in which an incorrect amount set up on the key-board may be corrected merely by the depression of the correct key in the orders where the errors are made without depression or manipulation of additional keys.

Other and further objects and advantages of the invention will be made apparent hereinafter.

In the drawings,

Fig. 1 is a right side sectional elevation of my

improved cash register illustrating only the essential parts thereof;

Fig. 2 is a front detail view of a number of the key lock levers or pendants as modified for application to my present invention;

Fig. 3 is a perspective view from the right side of the machine showing the pre-set key, the paid out key, the dollar key, the twenty cent key in depressed position, and the five cent key in normal position;

Fig. 4 is an enlarged detail view of the pre-set bail; and

Fig. 5 is similar to Fig. 4 showing the manner of releasing the incorrect key upon depression of the correct key of the same order.

The illustrated cash register is known as a key-operated cash register and the mechanism is preferably mounted and carried between right and left side plates 10 which support the entire mechanism and are maintained in spaced relation by tubular members (not shown) and the various shafts of the cash register mechanism. The mechanism includes a plurality of rows of depressible key levers 11 of the necessary denominations and numbers in each denomination, although for convenience and greater clarity of description only a single key lever of each denomination or order has been illustrated in the drawings. The key levers are journaled on a cross shaft 12 secured to the end plates 10 and are urged clockwise about shaft 12 by springs 13, the upward movement of the key levers being limited by a comb plate 14. Each key lever has a rearwardly and upwardly extending arm 16 which engages a hollow cross shaft 17 carried at each end by one arm of a full stroke lever 18 journaled on shaft 12 adjacent each end thereof. Levers 18 have forwardly extending horizontal arms 19 to which are secured tension springs 20 which urge the full stroke levers 18 in a clockwise direction. Shaft 17 extends through slots 22 in the side plates 10, the slots limiting the rocking movement of shaft 17 and levers 18 which constitute a universal bail. The full stroke levers 18 terminate at their upper ends in sectors 23 engaged by pawls 24 which insure a full stroke being made each time levers 18 are rocked by the keys 11. The upper end of each key lever arm 16 has a differential cam slot 25 therein, which differentially actuates the register (not shown) and the indicating mechanisms 26 shown and described in detail in my aforesaid co-pending applications.

Shaft 17 also supports for bodily movement therewith a key coupler 26 freely pivoted thereon

and having an upwardly extending finger 27 normally urged clockwise into contact with a stud 28 by springs 29, the stud 28 serving to hold the key coupler 26 in inoperative or non-coupling position. Upon partial depression of any key, the forward movement of shaft 17 carrying with it coupler 26 permits clockwise rotation of the coupler about its pivot by springs 29 to move its depending lip 30 into the path of movement of projections 32 extending from each of the arms 16 of the key levers 11 whereby the keys may be coupled or latched to the key coupler 26. Upon further depression of any one key, all the latched keys are carried downwardly because of the bodily movement of the coupler 26 with the depressed keys. The foregoing mechanism is made the subject of my prior Patents Nos. 2,070,059 and 2,070,060, issued February 9, 1937 to which reference is made for further details.

20 The machine also embodies a pre-set mechanism which comprises a key lever 33 pivoted to the left side plate 10 at 34 and urged in a clockwise direction by a tension spring 35. A forwardly extending arm of the pre-set key lever 25 has an auxiliary or extension lever 33^a detachably secured thereto providing for the removal of the lever 33^a to facilitate the removal of the case of the machine without requiring removal of the key lever 33. Formed in the downwardly extending arm 33^b of pre-set lever 33 is an inverted L-shaped cam slot 36 (Fig. 1) in which rides a stud 37 carried by the forwardly extending arm 19 of the left full stroke lever. As the pre-set key is depressed, the pre-set key lever 33 is rocked counterclockwise, stud 37 is moved downwardly and rocks the full stroke lever 18 counterclockwise or forward to the position illustrated in Fig. 3 and causes the pawl 24 to lodge in the first notch of the sector 23. The upper finger 27 moving counterclockwise with the lever 18 is disengaged from the stud 28, thus allowing the spring 29 to move the key coupler in a clockwise direction into coupling position, i. e., into the path of the projections 32 of the key levers 45 11. The above operation places the machine in pre-set position and the amount keys can then be partially depressed and latched to the key coupler.

In setting up or indexing the keyboard, provision is made for locking each denomination of keys; that is, the cents keys, the dimes keys, the dollars keys, and the character keys as groups to the coupler 26. For this purpose, rear depending lip 30 of the coupler is formed with stepped sections as at 31 (Fig. 3), the sections being successively of greater height from the cents keys to the character keys. In indexing the keyboard when the machine is in pre-set position, it is necessary to depress the highest desired denomination first and the lowest last because, if the keys of higher orders were depressed last, the coupler 26 is raised sufficiently to release each lower order key because the portion of the lip for the cents order is not as great as that for the higher orders.

The lower rear portion of the coupler lip 30 is chamfered or beveled as at 30^b (Figs. 4 and 5) so that when the keys 11 are depressed and the projections 32 of the key levers 11 are moved forwardly into engagement with the key coupler lip, the coupler will be rocked upwardly against the urge of spring 29 by contact of the projections 32 with the beveled edge 30^b to allow the projections 32 to move forwardly under the lip 30, after which the coupler will drop rearwardly of the

projections and latch the depressed keys in pre-set position.

It is possible that when one key has been erroneously depressed and is held in pre-set position by the key coupler 26 and a second or corrected key of the same order is partially depressed, the coupler 26 may be raised sufficiently to permit the second key lever to pass under the coupler lip 30 and be latched thereby without allowing sufficient time for the first depressed key to be restored to normal position. Thus, the second key could be depressed to cause the coupler 26 to be raised and lowered before the first key of the same order could move rearwardly from its last pre-set position under the coupler 26 with the result that two keys of the same order may become latched to the key coupler.

To overcome the above difficulty, applicant has devised means by which the first depressed incorrect key may be partially restored to normal position before the second key of the same order has raised the key coupler 26 the required distance to permit its projection 32 to pass under the coupler 26 and become latched thereto. Referring to Fig. 4, the lower front portion of the depending lip 30 of the key coupler is chamfered or cut away as at 30^a at the angle indicated by the dot and dash lines A—A. The path of travel of the key projection 32 is indicated by the line B—B. Therefore, as viewed in Fig. 5, when the second key is being depressed and the projection 32 of the second key is still raising the coupler 26, the projection 32 of the first key moves rearwardly under the lip 30. When the second key is depressed sufficiently so as to allow the projection 32 to pass to pre-set position under lip 30, the projection 32 of the first key will have had sufficient time to move from under the coupler to normal position. Thus, restoration of the first depressed key before the coupler 26 latches a second key in position is insured.

Provision is made to prevent overthrow of the full stroke sectors when the machine is placed in pre-set position and to limit the movement of the pawl 24 to the first notch of the sector 23. When the pre-set key is fully depressed, the stud 37 enters in a notch 36^a formed in the forward end of the horizontal portion of the cam slot 36 and overthrow of the full stroke sectors is thereby prevented. After depression of the pre-set key, it is held in the depressed position by engagement of an upstanding arm 38 forming one side of the cam slot 36 of the pre-set key with the stud 37, the latter being held exterior of the vertical portion of the cam slot 36^a. If the machine is given a stroke of operation following depression of the pre-set key, the stud 37 moves downwardly along the edge of the arm 38 exterior of the cam slot 36 retaining the pre-set key in depressed position until the end of the return stroke, at which time the stud 37 is restored to the horizontal portion of the cam slot 36. When the machine is given a stroke of operation without first depressing the pre-set key, stud 37 moves up and down in the vertical portion of the cam slot 36 and depression of the pre-set key during machine operation is prevented.

Means are provided to lock the paid out key against depression until the pre-set key has conditioned the machine to pre-set position. As shown in Fig. 1, a latch 40 pivotally carried by the paid out key lever 11 is provided with a notched end 40^a for locking engagement with a stud 41 carried by a rearwardly extending arm of the pre-set lever when the pre-set lever and the

paid out lever are in normal position. A tension spring 42 urges the latch 40 in a clockwise direction into latching engagement with the stud 41, and its movement is limited by the engagement 5 of stud 39 with an arm 40^b of the latch 40. After the pre-set lever 33 is depressed and rocked counterclockwise, stud 41 is moved rearwardly out of engagement with the notched end 40^a, and operation of the paid out key is permitted in the 10 usual manner.

In the machine disclosed in applicant's heretofore mentioned co-pending applications, only one key of a single denomination or order could be partially depressed at a time. This was accomplished by well-known pendant interlocks 45. However, referring to Fig. 2 of applicant's drawings, it will be noted that the cam edges 44 of the key locks 45 have been cut away at the upper ends to permit limited depression of a second key 15 of the same order to pre-set condition. Thus, a second key in any order can be depressed to pre-set position and as a second key of any order is so depressed, the key coupler 26 is raised by the projection 32 of the second key and the 20 first depressed key of the same order and the keys of all lower orders are simultaneously released to normal position. This permits depression of a second key in an order and prevents latching of two keys of the same order in pre-set position.

From the foregoing description, the operation of the machine is apparent. The pre-set key lever may first be depressed to place the machine in pre-set position and, if the desired amount to 35 be indexed on the keyboard is \$1.25, the dollar key is first depressed to pre-set position followed by the twenty key next and the five key last, after which any one of these keys may be fully depressed to complete the entry. Should the operator inadvertently depress the six key of the 40 units order to pre-set position so that the entry if completed would read \$1.26 on the indicator instead of \$1.25, the error may be easily corrected. In this instance, it is necessary merely 45 to depress the five key of the units order. This releases the six key from pre-set position and the five key is latched in pre-set position. If the error is made in the tens order so that the amount \$1.35 was indexed instead of \$1.25, depression of the correct twenty key of the tens 50 order would release the incorrect thirty key to normal position and latch the twenty key in pre-set position. In correcting this error, the key of the lower order, namely, the five key of the 55 units order would be automatically released and so must be redepressed to pre-set position. However, the keys of the higher orders remain undisturbed by any manipulation of the keys of the lower orders.

Although the foregoing description has set forth one form of flexible keyboard device, it will be understood that changes and modifications may be resorted to without departing from the spirit and scope of the invention as defined in 60 the appended claims.

I claim:

1. In a cash register, a plurality of depressible keys of the desired denominations, and a key coupler having coupling portions adapted to latch 65 said keys thereto upon partial depression of said keys, said coupling portions being so constructed and arranged that keys of denominations of other than those previously latched to said coupler may be latched thereto, said coupling portions also 70 being so constructed and arranged that a pre-

viously depressed key of one denomination may be released by partial depression of a second key of the same denomination to latching position with said coupling portions.

2. In a cash register, a plurality of depressible keys of the desired denominations, and a key coupler normally held out of engageable position with said keys and being releasable upon partial depression of said keys to engageable position with said keys, said coupler being capable 10 of limited movement when in engageable position and having coupling portions so constructed and arranged that keys of denominations other than those previously engaged may be engaged while said coupler is in engageable position and 15 said coupling portions also being so constructed and arranged that a previously depressed key of one denomination may be released by partial depression of a second key of the same denomination to engageable position with the key coupling 20 portions.

3. In a key-operated cash register, a plurality of depressible keys of the desired denominations adapted to be partially depressed to pre-set position and fully depressed to operate said 25 cash register, and a single unitary key coupler normally held out of engageable position with said keys and being releasable upon partial depression of said keys to engageable position with all of said keys, said coupler being capable of 30 limited movement when in engageable position and having coupling portions so constructed and arranged that keys of denominations other than those previously engaged may be engaged while said coupler is in engageable position and said 35 coupling portions also being so constructed and arranged that a previously depressed key of one denomination may be released by partial depression of a second key of the same denomination to engageable position with the key coupling 40 portions.

4. In a cash register, a plurality of depressible keys of the desired denominations, interlocks for each denomination of keys arranged to permit partial depression of a plurality of keys of one 45 denomination and to prevent depression of a plurality of keys in one denomination beyond partially depressed position, and a key coupler having coupling portions adapted to latch said keys thereto upon partial depression of said 50 keys, said coupling portions being so constructed and arranged that keys of denominations of other than those previously latched to said coupler may be latched thereto, said coupling portions also being so constructed and arranged 55 that a previously depressed key of one denomination may be released by partial depression of a second key of the same denomination to latching position with said coupling portions.

5. In a key-operated cash register, a plurality 60 of depressible pivoted keys of the desired denominations, pendant interlocks arranged to permit limited partial depression and prevent full depression of a plurality of keys in the same denomination, and a single unitary key coupler 65 normally held out of engageable position with said keys and being releasable upon partial depression of said keys to engageable position with all of said keys, said coupler being capable of limited movement when in engageable position 70 and having coupling portions so constructed and arranged that keys of denominations other than those previously depressed may be engaged while said coupler is in engageable position, said coupling portions also being so constructed and ar- 75

ranged that a previously depressed key may be released by partial depression of a second key to engageable position with the key coupling portions prior to coupling of said second key.

5 6. In a cash register, a plurality of depressible key levers of the desired denominations, and a key coupler comprising a crossbar of sufficient length to extend across the desired number of key levers and having a depending longitudinal 10 lip adapted to engage the key levers, said lip being chamfered along its lower portion so that a previously depressed latched key may be released to normal position by partial depression of a second key to engageable position with said 15 lip.

7. In a cash register, a plurality of depressible key levers of the desired denominations, and a key coupler comprising a cross bar of sufficient length to extend across the desired number of 20 key levers and having a depending longitudinal lip adapted to engage the key levers, said lip being chamfered along its lower front portion so that a previously depressed latched key may be released to normal position by partial depression 25 of a second key to engageable position with said lip prior to coupling of said second key to said lip.

8. In a key-operated cash register, a plurality of depressible keys adapted to be partially depressed to pre-set position and fully depressed to operate said cash register, pendant interlocks for each denomination of keys constructed and arranged to permit limited partial depression and prevent full depression of a plurality of keys 30 in the same denomination, and a key coupler comprising a cross-bar of sufficient length to extend across the desired number of key levers having a depending longitudinal lip adapted to engage the key levers, said lip being chamfered 35 along its lower portion so that the previously depressed latched key of a denomination may be released to normal position by partial depression of a second key to engageable position with the lip portion prior to coupling of said second key.

40 9. In a key-operated cash register, a plurality of depressible keys adapted to be partially depressed to pre-set position and fully depressed to operate said cash register, pendant interlocks for each denomination of keys constructed and arranged to permit limited partial depression 45

50

and prevent full depression of a plurality of keys in the same denomination, and a key coupler comprising a cross-bar of sufficient length to extend across the desired number of key levers, having a depending longitudinal lip adapted to 5 engage the key levers, said lip being chamfered along its lower front portion so that the previously depressed latched key of a denomination may be released to normal position by partial depression of a second key to engageable position with the lip portion prior to coupling of said 10 second key.

10 11. In a key-operated cash register, a plurality of depressible key levers of the desired denominations adapted to be partially depressed to pre-set position and fully depressed to operate said cash register, pendant interlocks constructed and arranged to permit limited partial depression and preventing full depression of a plurality of keys in the same denomination, and a single 15 unitary key coupler comprising a crossbar of sufficient length to extend across the desired number of key levers, a pre-set key for moving said coupler from inoperative position to operative pre-set position in the path of movement 20 of said key levers, said coupler having a depending longitudinal lip on the key coupler adapted to engage the key levers, said lip being chamfered along its lower front portion so that a previously depressed latched key may be released to normal position by partial depression 25 of a second key to engageable position with the lip portion prior to coupling of said second key.

15 11. In a key-operated cash register, a plurality of depressible key levers of the desired denominations, a key coupler comprising a crossbar of sufficient length to extend across the desired number of key levers, a pre-set key for moving said coupler from inoperative position to operative pre-set position in the path of movement of 30 said keys, said coupler having a depending longitudinal lip on the key coupler adapted to engage the key levers, said lip being chamfered along its lower front portion so that a previously depressed and coupled key of one denomination 35 may be released to normal position by partial depression of a second key to engageable position with the lip portion prior to coupling of said second key to said key coupler.

WALTER J. PASINSKI.
